DEMONSTRATION SET

Marshall B. Adams, Warren, Ohio, assignor to
 Mullins Manufacturing Corporation, Salem,
 Ohio, a corporation of New York

Application February 24, 1941, Serial No. 380,139

10 Claims. (Cl. 35—18)

The invention relates generally to demonstration sets, and more particularly to apparatus for representing on a small scale a room provided with equipment such as cabinets and the like, in a variety of arrangements.

In planning the building or remodeling of homes, and especially a modern kitchen equipped with factory built cabinets, it is desirable to show a prospective customer how a completed installation will appear, and this is conveniently done by using small scale or miniature representations of the walls of a room with small scale models of kitchen equipment arranged along said walls as desired.

The room walls and floor of the demonstration set are conveniently and cheaply made of heavy stiff paper-board, and the kitchen equipment models may be and are preferably cut-outs of cardboard and the like which are printed and scored for folding into three-dimensional models. A large number and variety of these models can be packed flat with the paper-board room and floor members in a relatively small space in an envelope or other container.

In setting up a demonstration it has been necessary to remove the paper-board room and floor members and the cardboard equipment models from the container, lay the container aside, and then set up the wall and floor members on a table top or the like. Means must be provided for maintaining the wall members vertical and in proper position on the floor member, which may be marked with a suitable scale so that rooms of various sizes can be properly represented.

It is very inconvenient and awkward to keep these paper-board wall and floor members in proper relative position while the cardboard models are moved about and mounted on the wall members to obtain a desired arrangement of the equipment in the room, and consequently the wall members are frequently knocked over and the set-up disarranged.

It is therefore an object of the present invention to provide an improved demonstration set including a novel container box in which the wall and floor members are constructed, arranged and secured in such a way that when the container is opened said wall and floor members are supported within the container in proper relationship for receiving and mounting the kitchen equipment models in various arrangements.

Another object is to provide improved means for detachably mounting the equipment models in folded form on the wall members.

A further object is to provide an additional

wall member detachably fitting within the improved container, and having improved means thereon for movably supporting it on the floor member of the container when opened.

5 A still further object is to provide a simple and inexpensive construction incorporating all of the foregoing objectives and easily and effectively used as a demonstration set.

These and other objects are accomplished by 10 the novel parts and improvements and the novel container comprising the present invention, a preferred embodiment of which is shown by way of example in the accompanying drawings.

In general terms the invention may be stated 15 as including an improved container box adapted for enclosing all of the parts of a demonstration set, said box having a lid hinged to its back wall, a floor member secured to said back wall folded within the box when closed and adapted to rest 20 on the inside of the lid when opened, a two-leaved folded room member having a first leaf secured to the bottom wall of the box and a second leaf adapted to unfold to a position at right angles to the first leaf for representing two walls of a 25 room at right angles to the floor member, and a third wall member having means for supporting it at right angles to said first leaf and to the floor member, said wall members having improved hanger means on which to hang cardboard equipment models in folded form.

Referring to the drawings forming part hereof:

Figure 1 is an exterior isometric view of the 35 improved container box in closed position for containing all of the parts of the demonstration set;

Fig. 2 is a transverse sectional view thereof as on the plane of lines 2—2, Fig. 1;

Fig. 3 is an isometric view with parts broken 40 away of the improved container box in open position and resting on the rear wall and lid, with the wall and floor members partially unfolded.

Fig. 4 is a detached isometric view of the additional wall member showing the supporting easel thereon in flat folded condition;

Fig. 5 is an isometric view similar to Fig. 3 showing the wall and floor members fully unfolded and the additional wall member in position on the floor member with the easel unfolded to supporting position;

Fig. 6 is a transverse sectional view as on the 45 plane of lines 6—6 showing one of the foldable wall cabinets hung in position on the additional wall member;

Fig. 7 is an enlarged fragmentary sectional view similar to Fig. 6;

Fig. 8 is a plan view of one of the improved foldable wall cabinets in flat unfolded position; and

Fig. 9 is an isometric view of the wall cabinet of Fig. 8 in partially folded position; and

Fig. 10 is a perspective view of the improved container box in open position with the wall and floor members properly positioned and fully opened and a desired arrangement of the foldable equipment models mounted thereon to represent a completed kitchen installation.

Similar numerals refer to similar parts throughout the several views of the drawings.

Referring first to Figs. 1, 2 and 3, the improved container box is preferably a rectangular or six-sided box of usual appearance, and includes a bottom wall 11, side walls 12 and 13, front wall 14 and rear wall 15. A lid 16 is hinged or foldably connected to the top edge of rear wall 15 as at the fold line 17, and is provided at its other three marginal edges with downturned flanges 18 for overlapping the side walls 12 and 13 and the front wall 14 when the box is closed.

The floor member which represents the floor of a room in miniature is preferably constructed of heavy stiff paperboard or cardboard and includes a portion 19 positioned flat against and secured by adhesive or other means to the inside of rear wall 15, as best shown in Fig. 2. The floor member also includes another portion 20 which is hinged or foldably connected to the portion 19 as at or near the hinge connection 17 of the lid, as at the fold line 21, and the fold line 21 is parallel to the fold line 17 of the lid. The portion 20 of the floor member is adapted to fold across the top of the box in closed position within the lid 16 and may rest on the top of the front wall 14 as shown in Fig. 2. When the lid is swung open through 90° so that it extends in coplanar continuation of the rear wall 15, the floor member portion 20 may be similarly swung open so that it rests on the lid 16 and is in coplanar continuation of the floor member portion 19. Accordingly, if the box is turned as shown in Fig. 3 so that the rear wall 15 and lid 16 rest on a flat supporting surface, the portions 19 and 20 of the floor member form a flat floor when unfolded.

As shown the floor member 19, 20 is preferably provided with a layout of parallel lines intersecting to form squares, and the respective lines are marked with a convenient scale so that a room of proportionate size may be arranged on the floor member.

A wall member for representing two adjoining walls of a room is provided within the container box and preferably consists of two leaves 22 and 23 foldably connected or hinged at one edge 25. The leaves of the wall member may be made of heavy stiff paper-board similar to the material of which the floor member is made, and are adapted to be folded flat abutting and mating with each other when the box is closed as indicated in Fig. 2.

The portion 22 of the wall member is positioned flat against the bottom wall 11 of the box and is secured thereto by adhesive or other means. The rear edge 26 of the wall portion 22 substantially abuts the portion 19 of the floor member, so that when the box is opened and the portion 23 of the wall member unfolded or swung towards open position as indicated in Fig. 3, the bottom edges 26 and 27 of the wall member portions 22 and 23 will lie closely adjacent to the floor member 19, 20.

Thus as shown in Figs. 3 and 5, when the lid of the box is open and the lid and rear wall of

the box support the floor member portions 19 and 20 in flat position, the wall member portion 23 may be swung open to a position at right angles to the wall member portion 22, and the wall member portions 22 and 23 will be at right angles to the floor member. Accordingly, the two walls and floor of a room are represented in proper relation, and the box and floor and wall members are tied together to maintain and support the floor and wall members in this desired position.

An additional wall member indicated at 28 is provided for use where it is desired to represent three adjoining walls of a room. The additional wall member 28 is preferably a single sheet of heavy paper-board material similar to the material of which the other wall members and floor member are made, and is adapted to stand on edge on the floor member in open position at right angles to the wall member portion 22 and parallel to the wall member portion 23 as indicated in Fig. 5.

The additional wall member 28 is preferably of substantially the same size as the wall member portions 22 and 23 and consequently fits nicely within the container box in closed position as indicated in Fig. 2. Means for movably supporting the wall member 28 in upright position on the floor member 19, 20 so that the wall member 28 can be moved toward and away from the wall member portion 23 as desired, preferably includes a foldable easel 29 secured to the exterior side of the wall member 28.

As shown in Figs. 4, 5 and 6, the easel 29 includes a front wall 30 adhesively secured to the wall member 28 and having side portions 31 foldably connected to its laterally opposite edges. The side portions 31 are connected by a rear wall 32 which is foldably connected to the side portions 31 at the score lines 33. The rear wall 32 has an upper extension 34 foldably connected thereto at the score line 35, and the upper edge of the extension 34 is provided with spaced notches 36.

The upper edges of the side portions 31 are provided with under cut ears 37 which are adapted to engage in the notches 36 when the easel is unfolded or expanded to rectangular form, as indicated in Figs. 5 and 5.

As shown in Figs. 2 and 4, the easel 29 may be swung laterally of the wall member 28 and folded flat against the same, and when unfolded to rectangular form with the ears 37 engaged in the notches 36, the bottom of the rear wall member 32 has a depending leg 32a which stands on the lid 16 or the support therefor or on the floor member 19, 20 to movably support the wall member 28 thereon.

The improved demonstration set includes a plurality of equipment models for representing a kitchen sink, refrigerator, stove and a variety of kitchen cupboards or cabinets. These equipment models are preferably foldable cardboard and are printed and scored flat and adapted to be folded to represent three-dimensional cabinets and the like. The equipment models may conveniently be printed and scored on cardboard sheets of a size which will fit easily within the container box, and the outlines of the various models are preferably cut all around except at two or three points so that they may be pushed out of the sheets easily when desired.

In Fig. 2 a plurality of these cardboard sheets containing various cut out models of kitchen equipment is indicated at 38, and as shown the

sheets may be conveniently stacked within the box on top of the folded wall members 22 and 23 and the additional wall member 28.

The foldable cardboard models which represent wall cabinets and are adapted to be mounted along the upper portions of the wall members are all constructed substantially identical with each other except for their dimensions, and accordingly only one of these foldable models is illustrated in detail as shown in Figs. 8 and 9. In Fig. 8 the wall cabinet indicated generally at 38 includes a front panel 40 bounded at its side edges by score lines 41 and at its top edge by score line 42. Side panels 43 are hinged to the front panel at the score lines 41 and a top panel 44 is hinged to the front panel at the score line 42.

The side panels 43 have at their top edges foldable tabs 45 in which U-shaped cuts 46 are made, and the top panel 44 has at its side edges tabs 47 which are adapted to be bent downwardly and inserted in the cuts 46 when the tabs 45 are folded rearwardly. This arrangement, when folded as indicated in Fig. 9 provides a rectangular three-dimensional cabinet model.

For the purpose of hanging the wall cabinet models such as 39 on the wall members, a hanger tab 48 is provided at the top edge of the top panel 44 in flat position, which becomes the rear edge of the top panel when the cabinet model is folded. This hanger tab 48 is adapted to be folded downwardly about the score line 49 as indicated in Fig. 9.

Means for receiving the hanger tabs of the wall cabinet models for mounting the same on the wall members preferably includes improved hanger strips, one on each of the wall members 22, 23 and 28 and extending along the wall members at a position calculated to locate the wall cabinet models at the correct proportional distance below the top of the wall members and above the base cabinet models arranged on the floor.

The improved hanger strips are indicated generally at 50 and include a lower portion 51 extending along and adhesively secured to the wall member, and an upper portion 52. Between the lower and upper portions of the hanger strips an indentation 53 is provided which extends throughout the lengths of the hanger strips. This indentation causes the upper portion 52 to stand slightly away from the wall member so that the hanger tabs 48 of the wall cabinet models can be inserted easily behind the portion 52 of the hanger strip at any position along the same.

The construction of the base cabinet models representing the refrigerator 54 (Fig. 10) the stove 55, the sink 56, and the various base cabinets 57 is identical with the wall cabinets 38 except that the hanger tab 48 may be omitted since all of the base cabinets are supported on the floor member.

For the purpose of representing a complete kitchen cardboard models may be provided of windows and doors, one such window being indicated at 58 in Fig. 10 and being merely a sheet of cardboard with a hanger tab 48 similar to the hanger tabs 43.

In making a demonstration set up for a room of given dimensions, the improved container box 70 is opened and the sheets of cardboard models 38 removed, after which floor member 19, 20 and the wall members 22 and 23 may be unfolded as indicated in Fig. 3. The desired cardboard 75

equipment models are then removed individually in flat condition from the sheets 38 and folded into three-dimensional form in the manner shown in Fig. 9. By referring to the scale lay 5 out on the floor member, the dimensions of any given kitchen can be marked off and the doors and windows of the given room represented by the cardboard models therefor located in proper relationship on the wall members. If three sides 10 of the room are desired to be represented, the additional wall member 28 is set up as previously described and positioned on the floor member at the proper proportional distance from the wall member 28.

15 A selection of various kitchen cabinets and equipment can then be made from the cardboard models and these positioned along the wall members to obtain any desired arrangement thereof, a typical arrangement being shown in Fig. 10.

20 The improved demonstration set provides for maximum flexibility in selecting and arranging the kitchen equipment models, because the base models can be moved about as units and tried in various arrangements, and the same is true of

25 the wall models which are easily detached from or slid along the hanger strips 50 to be replaced at different positions. Once the cardboard equipment models are folded the choice of a desired arrangement merely entails moving the 30 models about from place to place along the walls until a desired arrangement is obtained, without requiring any cutting or pasting or further folding of any of the parts.

35 After a demonstration has been completed, the equipment models can be removed from the walls and left in their folded form, and after the wall members 22, 23 and 28 are folded and placed flat within the box, the equipment models in folded form can be placed on top of the same 40 within the extra space provided under the lid of the box, after which the floor portion 20 is folded as shown in Fig. 2 and the box closed. Thus when another demonstration is desired the equipment models are folded and ready to be applied 45 to the wall members.

I claim:

1. A demonstration set for representing a portion of a room in miniature including a rectangular box container having a bottom wall, a back wall, and a lid hinged to said back wall, said lid being adapted when opened to extend in the same plane as said back wall, a floor member having a portion secured to the inside of said back wall and a hinged portion adapted to fold 55 within the box when closed and to rest flat on the lid when opened, a two-leaved foldable wall member having a first leaf secured to the inside of the bottom wall and a second leaf adapted to unfold at right angles thereto when the lid is in open position, another wall member adapted to be enclosed within the box, foldable means on said other wall member for movably supporting the same on and at right angles to said floor member when the floor member is unfolded, a plurality of foldable equipment models contained within the box and adapted to be folded to three-dimensional shapes, and hanger means on the wall members below the tops thereof for hanging said equipment models at desired positions on said wall members.

2. A demonstration set for representing a portion of a room in miniature including a rectangular box container having a bottom wall, a back wall, and a lid hinged to said back wall, said lid being adapted when opened to extend in the same

plane as said back wall, a floor member having a portion secured to the inside of said back wall and a hinged portion adapted to fold within the box when closed and to rest flat on the lid when opened, a two-leaved foldable wall member having a first leaf secured to the inside of the bottom wall and a second leaf adapted to unfold at right angles thereto when the lid is in open position, a plurality of foldable equipment models contained within the box and adapted to be 10 folded to three-dimensional shapes, and hanger means on said wall member below the top thereof for hanging said equipment models at any desired positions on said wall member.

3. A demonstration set for representing a portion of a room in miniature including a rectangular box container having a bottom wall, a back wall, and a lid hinged to said back wall, said lid being adapted when opened to extend in the same plane as said back wall, a floor member having a portion secured to the inside of said back wall and a hinged portion adapted to fold within the box when closed and to rest flat on the lid when opened, a two-leaved foldable wall member having a first leaf secured to the inside of the bottom wall and a second leaf adapted to unfold at right angles thereto when the lid is in open position, a plurality of equipment models contained within the box, and means on said wall member below the top thereof for hanging said models at any desired positions along said wall member.

4. A demonstration set for representing a portion of a room in miniature including a rectangular box container having a bottom wall, a back wall, and a lid hinged to said back wall, said lid being adapted when opened to extend in the same plane as said back wall, a floor member having a portion secured to the inside of said back wall and a hinged portion adapted to fold within the box when closed and to rest flat on the lid when opened, a two-leaved foldable wall member having a first leaf secured flat to the inside of the bottom wall and a second leaf adapted to unfold at right angles thereto when the lid is in open position, another wall member adapted to be enclosed within the box, foldable means on said other wall member including a depending leg spaced from said wall member when unfolded for movably supporting the same on and at right angles to said floor member when the floor member is unfolded, a plurality of equipment models contained within the box, and means on said wall members below the tops thereof for hanging said models at any desired positions along said wall members.

5. A demonstration set for representing a portion of a room in miniature including a rectangular box container having a bottom wall, a back wall, and a lid hinged to said back wall, said lid being adapted when opened to extend in the same plane as said back wall, a floor member having a portion secured to the inside of said back wall and a hinged portion adapted to fold within the box when closed and to rest flat on the lid when opened, a two-leaved foldable wall member having a first leaf positioned flat against said bottom wall and a second leaf adapted to unfold at right angles thereto when the lid is opened, hanger strips extending along the leaves of said wall member, and a plurality of equipment models contained within the box and adapted to hang on said hanger strips at any desired positions along the same.

6. A demonstration set for representing a por-

tion of a room in miniature including a rectangular box container having a bottom wall, a back wall, and a lid hinged to said back wall, said lid being adapted when opened to extend in the same plane as said back wall, a floor member having a portion secured to the inside of said back wall and a hinged portion adapted to fold within the box when closed and to rest flat on the lid when opened, a two-leaved foldable wall member having a first leaf positioned flat against said bottom wall and a second leaf adapted to unfold at right angles thereto when the lid is opened, another wall member adapted to be enclosed within the box, foldable means on said other wall member including a depending leg spaced from said wall member when unfolded for movably supporting the same on and at right angles to said floor member when unfolded, hanger strips extending along all said wall members, and a plurality of equipment models contained within the box and adapted to hang on said hanger strips at desired positions along the same.

7. A container for a demonstration set for representing a portion of a room in miniature comprising a six-sided box, one side being a lid hinged to the rear side wall, said lid being adapted when opened to extend in the same plane as said rear side wall and said lid when opened and rear side wall being adapted to rest on a flat supporting surface, a floor member within the box having a portion secured to said rear side wall and a hinged portion adapted to rest flat on said lid when opened, a wall member within the box having a portion secured to the side wall opposite the lid and having a hinged portion adapted to swing open at right angles to said first wall portion and to said floor member, and hanger strips on said wall member adapted for supporting equipment models thereon.

8. A container for a demonstration set for representing a portion of a room in miniature comprising a six-sided box, one side being a lid hinged to the rear side wall, said lid being adapted when opened to extend in the same plane as said rear side wall and said lid when opened and rear side wall being adapted to rest on a flat supporting surface, a floor member within the box having a portion secured to said rear side wall and a hinged portion adapted to rest flat on said lid when opened, a wall member within the box having a portion secured to the side wall opposite the lid and having a hinged portion adapted to swing open at right angles to said first wall portion and to said floor member.

9. In combination with a container for a demonstration set for representing a portion of a room in miniature comprising a six-sided box including rear and bottom side walls at right angles to each other, the top side being a lid hinged to the rear side wall and being adapted to swing open to extend in the same plane as said rear side wall, and said lid when opened and rear side wall being adapted to rest on a flat supporting surface when the lid is opened, a floor member within the box having a portion secured to said rear side wall and a hinged portion adapted to rest flat on said lid when opened, a wall member within the box having a portion secured flat against said bottom wall and having a hinged portion adapted to swing open to a position at right angles to said bottom wall and to said floor member when opened, another wall member within the box, and foldable easel means on said other member including a depending leg spaced from said wall member when

unfolded for movably supporting the same on said floor member at right angles thereto.

10. A container for a demonstration set for representing a portion of a room in miniature comprising a six-sided box including rear and bottom side walls at right angles to each other, the top side being a lid hinged to the rear side wall at its top edge and being adapted when opened to extend in the same plane as said rear side wall, a floor member having a portion secured to said rear side wall and a portion hinged

thereto adjacent and parallel to the hinged connection between the lid and rear side wall, the hinged portion of said floor member being adapted to fold within the box when closed and to rest flat on said lid when open, and a wall member within the box having a portion secured to said bottom wall and a foldable portion hinged thereto for swinging open to a position at right angles to said first wall member portion and to said floor member when opened.

MARSHALL B. ADAMS.
